UNITED STATES PATENT OFFICE

166,278

SLIPPER

Myer S. Silver, Brookline, Mass.

Application December 5, 1951, Serial No. 17,608

Term of patent 14 years

(Cl. D7—7)

To all whom it may concern:

Be it known that I, Myer S. Silver, a citizen of the United States of America, residing at Brookline, in the county of Norfolk and Commonwealth of Massachusetts, have invented a new, original, and ornamental Design for a Slipper, of which the following is a specification, reference being had to the accompanying drawing, forming part thereof.

Fig. 1 is a plan view of a slipper showing my new design; and

Fig. 2 is a perspective view looking toward the left side of the slipper shown in Fig. 1.

The right side of the slipper is substantially a mirror image of the left side.

I claim:

The ornamental design for a slipper, as shown and described.

MYER S. SILVER.
